(57) **CLAIM**

The ornamental design for a heart design for diamonds, as shown and described.

DESCRIPTION

FIG. 1 is a perspective view of a first embodiment of this invention;

FIG. 2 is a top plan view of this invention; and,
FIG. 3 is a bottom plan view of the invention shown in FIG. 1.

No side or front views are shown as they would merely be duplicative of showing the side edge of the raised portion of the heart from the side.

It being understood that the broken lines are for illustrative purposes only and form no part of the claimed design.
